(57) **CLAIM**

(**) Term: **15 Years**

The ornamental design for a textured fiber cement cladding panel, as shown and described.

(21) Appl. No.: **29/806,028**

(22) Filed: **Aug. 31, 2021**

(30) **Foreign Application Priority Data**

DESCRIPTION

Mar. 5, 2021 (EM) 008452197-0001

FIG. 1 is a front perspective view of a textured fiber cement cladding panel embodying our new design;

(51) **LOC (14) Cl.** **25-01**

FIG. 2 is a front view of the textured fiber cement cladding panel of FIG. 1;

(52) **U.S. Cl.**

FIG. 3 is a top view of the textured fiber cement cladding panel of FIG. 1, the bottom being a mirror image thereof;

USPC **D25/151**

FIG. 4 is a right side view of the textured fiber cement cladding panel of FIG. 1, the left side being a mirror image thereof; and,

(58) **Field of Classification Search**

FIG. 5 is an enlarged front view of the claimed portion of the

USPC D25/151

textured fiber cement cladding panel of FIG. 1.
